HOOP STICK

Guy P. Whitmore, 16207 Pomona Drive,
Detroit, Mich. 48240

Filed Aug. 14, 1967, Ser. No. 8,264

Term of patent 3½ years

(Cl. D34—5)

FIG. 1 is a front elevational view of a hoop stick showing my new design.

FIG. 2 is a side elevational view of the hoop stick.

FIG. 3 is a sectional view on line 3—3 of FIG. 1.

The side of the hoop stick opposite to that shown in FIG. 1 is plain and unornamented.

I claim:

The ornamental design for a hoop stick, substantially as shown and described.
